United States Patent Office

Des. 230,786
Patented Mar. 19, 1974

230,786

TRANSIT SEAT

Chester J. Barecki, Grand Rapids, Mich., assignor to
American Seating Company, Grand Rapids, Mich.

Filed Mar. 27, 1972, Ser. No. 238,744

Term of patent 14 years

Int. Cl. D6—01

U.S. Cl. D6—26

FIG. 1

FIG. 2

FIG. 3

FIG. 1 is an upper frontal perspective view of the inventive seat;

FIG. 2 is an upper rear perspective view of the seat of FIG. 1;

FIG. 3 is a view similar to FIG. 2 of the inventive seat without a rear cover;

FIG. 4 is a plan view of the seat of FIG. 1;

FIG. 5 is a front elevation view of the seat of FIG. 1; and

FIG. 6 is a side view of the seat of FIG. 1.

I claim:

The ornamental design for a transit seat, as shown.
